(57) **CLAIM**

The ornamental design for a refueling pipe, as shown and described.

DESCRIPTION

FIG. 1 is a top and right side perspective view of a refueling pipe, showing my new design;

FIG. 2 is a bottom and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 2;

FIG. 11 is an enlarged view of portion 11 in FIG. 2;

FIG. 12 is an enlarged view of portion 12 in FIG. 7; and,

FIG. 13 is an enlarged view of portion 13 in FIG. 8.

The evenly dashed broken lines illustrate features of the refueling pipe, and the unevenly dashed broken lines define the boundaries of the enlarged views. None of the broken lines form part of the claimed design.
